BRACELET LOCKET

Wilhelm Kuehner, Providence, R. I., assignor to
Excell Manufacturing Company, a corporation
of Rhode Island

Application February 21, 1941, Serial No. 380,019

5 Claims. (Cl. 63—19)

This invention relates to a locket.

Heretofore, it has been usual in the art of lockets to provide some arrangement for suspending the locket at the end of a chain or some flexible member; and while various devices which may carry exposed markings may have been used in a chain or bracelet, such for instance as identification tags, it is sometimes desirable that the marking carried be hidden from view.

One of the objects of this invention is to provide a locket having a cover for the contents which may be mounted in a bracelet whereby the character carried in the locket may be hidden from view until the cover is opened.

Another object of the invention is to provide a simple and inexpensive construction of locket which may be readily mounted in the chain.

A more specific object of the invention is the utilization of one of the walls of the locket for all of the attaching means for connecting the locket to the chain as well as the clasping of a cover which may be a separate piece associated therewith.

Another specific object of the invention is the utilization of the stock of one part of the locket for the provision of a catch and utilization of the stock of the other part of the locket as the co-operating means for clasping with the catch, and also as a finger piece for the opening of the cover from the body.

With these and other objects in view, the invention consists of certain novel features of construction, as will be more fully described and particularly pointed out in the appended claims.

In the accompanying drawing:

Fig. 1 is a perspective view illustrating the use of the device on the arm;

Fig. 2 is a perspective view of the locket alone;

Fig. 3 is a perspective view of the locket with the cover raised;

Fig. 4 is a perspective view of the body;

Fig. 5 is a perspective view of the cover;

Fig. 6 is a perspective view of the bezel contained in the body;

Fig. 7 is a perspective view of the identification tag;

Fig. 8 is a central sectional view through the locket and illustrating a chain as attached thereto.

In constructing the locket of this invention, I have utilized the stock of the body for forming the openings to which the chain may be connected, and also I have utilized the stock of the body and the stock of the cover for forming a

releasable clasp for these parts as well as a finger piece for opening them.

More particularly with reference to the drawing, 10 designates the body part, and 11, the cover which is hinged thereto. The body has a bottom wall 12 and opposite side walls 13, 13 bent up from the bottom wall. The stock of the bottom wall extends beyond the ends of the side walls 13 and is cut out as at 14 at one end to 10 provide a bail portion 15, while at the opposite end the stock 16 is slit and bent upwardly to provide an opening 17 and attaching bail 18. This portion 16 provides a latch from which there is a detent 19 deflected.

15 The cover 11 consists of a sheet of stock which is rolled as at 20 to provide a hinge eye for the reception of a pivot pin 21 therethrough and through the openings 22 in the side walls 13; or this member may be provided with integral 20 trunnions to pivot in such openings. At the opposite end the cover is rolled at 23 and the stock 24 of this roll is cut and raised to provide a catch portion 25. This catch 25 will snap beneath the detent 19 as shown in Fig. 8 so that the cover 25 will be releasably held in closed position while being easily raised by engagement with the finger portion 24.

25 Connectors 26 having arms 27 may be passed through the openings 14 and 17 and rolled into closed position while at the opposite end of the connectors 26 there are finger portions 28 to 30 flexibly connect to chain 29 which may encircle the wrist as shown in Fig. 1.

The walls 13 extend inwardly slightly beyond a 35 perpendicular to the wall 12 and a bezel designated generally 30 may be snapped between these walls to frictionally engage these walls and be retained in position, the side walls 31 of this bezel being tapered outwardly slightly to extend beneath the walls 12 for retaining such engagement. The bezel is cut away as at 32 providing a frame-like portion having side bars 33 and end bars 34 which are flanged to engage the inner surface of the bottom wall 12 and stand upwardly 40 from the wall so as to receive a plate member 35 having some character or identification number or other marking 36 thereon.

45 By this arrangement I may insert any member 35 within the locket beneath the bezel which retains it in place while the cover may be opened for exposure of this member or closed as shown in Fig. 2, the outer surface of which cover may have some embellishment or marking thereon if desired or may be left plain. The entire locket 50 may be a link in a bracelet chain to extend about

the wrist by being attached to the integral balls at the opposite ends thereof for use as shown in Fig. 1.

I claim:

1. A bracelet locket comprising a body having a bottom wall, the bottom wall at its opposite ends being provided with openings to which the ends of a bracelet may be attached, a cover hinged adjacent one end of the bottom wall and provided with a catch, the stock of the bottom wall being cut and deflected adjacent the said other end to provide a latch to engage said catch and releasably hold the cover in closed position and to form one of the said openings.

2. A bracelet locket comprising a body having a bottom wall and side walls extending therefrom, the bottom wall at its opposite ends being provided with openings to which the ends of a bracelet may be attached, a cover hinged to and between said side walls adjacent one end thereof, means adjacent the other end of the bottom wall to hold the cover in releasable clasped engagement, said cover being of a dimension to extend over the edges of the side walls and with the longitudinal edges thereof substantially flush with the outer surface of the side walls, and a bezel within said body for retaining a separable member.

3. A bracelet locket comprising a body having a bottom and side walls, the bottom wall at its opposite ends being provided with openings to which the ends of a bracelet may be attached, a cover comprising a single plate with the stock

thereof rolled at one end to provide a hinge part and cut and deflected at the other end to provide a catch part, said cover being hinged to and between the side walls adjacent one end of the bottom wall, means adjacent the other end of the bottom wall and formed from the stock thereof to hold the cover in releasable clasped engagement, and a bezel within said body frictionally engaging the said side walls for retaining a separable member.

4. A bracelet locket comprising a body having a bottom wall, an opening formed in the bottom wall at one end by cutting and deflecting the stock thereof upwardly to provide a latch, a cover hinged adjacent the other end of the body and provided with a catch to engage said latch, and a second opening provided in said bottom wall beyond said hinge connection of the cover, said openings being adapted to have the ends of a bracelet attached thereto.

5. A bracelet locket comprising a body having a bottom wall, an opening formed in the bottom wall at one end by cutting and deflecting the stock thereof upwardly to provide a latch, a cover hinged adjacent the other end of the body and provided with a rolled end from which a portion is cut and raised to provide a finger piece and catch to engage said latch, and a second opening provided in said bottom wall beyond said hinge connection of the cover, said openings being adapted to have the ends of a bracelet attached thereto.

WILHELM KUEHNER.
